UNITED STATES PATENT OFFICE

134,073

DESIGN FOR A DOG COLLAR

Samuel Johnson, Fort Lauderdale, Fla.

Application August 20, 1942, Serial No. 107,974

Term of patent 14 years

To all whom it may concern:

Be it known that I, Samuel Johnson, a citizen of the United States, residing at Fort Lauderdale, in the county of Broward and State of Florida, have invented a new, original, and ornamental Design for a Dog Collar, of which the following is a specification, reference being had to the accompanying drawing, forming part thereof.

I claim:

The ornamental design for a dog collar, as shown and described.

SAMUEL JOHNSON.
